UNITED STATES PATENT OFFICE.

CHARLES A. BENSON, OF CHICAGO, ILLINOIS.

PORTABLE SQUARE.

1,213,063.

Specification of Letters Patent. Patented Jan. 16, 1917.

Application filed January 30, 1911. Serial No. 605,664.

To all whom it may concern:

Be it known that I, CHARLES A. BENSON, a citizen of the United States, residing at Chicago, in the county of Cook and State of Illinois, have invented a new and useful Portable Square, of which the following is a specification.

My invention relates to improvements in folding squares or separable squares which have a joint, so that it can be folded or taken apart and put together for convenience at any time; and the objects of my improvements are, first, to make a square invisible joint at one of the inch marks; second, to make it so that when taken apart a smaller square will be apparent and useful when the larger one is not needed; third, to make a simple, cheap and durable device and other features to become apparent from the description to follow.

I am aware that several kinds of folding squares are being made and sold in the market. My invention avoids the difficulty to the least fractional degree of the square getting out of its 90 degrees angle, which is the most essential spirit of a square for all purposes.

I am aware that joints in wood and other materials have heretofore been made with tenons and dowels and tightened up with screws, bolts and nuts; but I am not aware that any joint of this, my construction, shown at A, and to be described in details to follow, has been made prior to my invention.

The joint consists of a suitable number of dowel pins, fixed solid to one part by its tight fitness in holes drilled to receive them, with small nicks or threads filed or cut on one end of the dowel-pins, to receive a blow from a hammer on one side of the part, right over where the nicks are in the hole, so as to make the dowel-pins substantially fastened to one of the parts. When inserted into the holes made to receive them in the other part, the projecting end of the center pin E is threaded to receive the brass screw-shell C, with diameter the same as the thickness of the blade, which is let into a perforation that has the threaded pin E in its center, here the joint can easily be tightened or loosened with no tool but the fingers, this prevents the parts from wearing out or breaking.

To describe my invention so that others versed in the art to which it pertains may

make and use the same, I have illustrated it on the accompanying sheet of drawings forming a part of this specification in which—

Figure 1, is a one side view, full size, with the three portions left out as it shows. Fig. 2 is a portion of same view, but it shows the appearance of the joint A, when taken apart. Fig. 3 is a cross section on the line 3—3 Fig. 2. Fig. 4 is a cross section on line 4—4 Fig. 2. Fig. 5 is a cross section on line 5—5 Fig. 2. Fig. 6 is a one-quarter size of an ordinary square, containing my invention, and showing the invisible joint at A.

Similar reference characters refer to similar parts throughout the several views.

The joint A is perfectly square with the edge, the same as the extreme end of the blade, and is almost invisible when closed, on account of being in one of the inch marks.

The perforation B is cut through the blade to give sufficient space to turn the screw-shell C with the fingers on both sides of blade.

The screw-shell C is to be made of brass or any suitable material, and threaded inside to fit tightly to the threaded center pin E, and to be made rough on the outside so that it can not slip in the fingers when turning the same; and to be made square at the ends, with length and diameter as shown, or to suit for any other purpose. Any suitable number of this screw-shell can be used to make the joint A sufficiently strong for this, or any other purpose.

The threaded retaining pin D is made the same as the dowel-pin E, which is fixed thereto to keep the screw-shell C, so it can not be lost when the square is taken apart.

The four dowel-pins F and center pins E and D are to be made of the best kind of steel, or any suitable material, for this, or any other purpose. The length and diameter can be made as shown, or it can be made to suit the purpose. These dowel-pins are to be pressed in tight into the holes drilled in about three-eighths of an inch into the part G, and a few nicks or threads are cut or filed on one side of the ends that go into the part G, and to receive a few strikes of a hammer, so as to make them securely fastened to the said part; the dowel-pins can also be screwed in on threads, but it would weaken them; unless it be made so that only a few threads be made on the end to be

screwed to a few threads that can be made in the bottom of the holes in the said part G. Any suitable number of the dowel-pins can be used to make the joint strong enough.

5 The center dowel-pin E is threaded on the projection beyond the other dowel-pins, so as to receive the screw-shell C, when inserted into the part H as shown in Fig. 1 and Fig. 6.

10 The four holes f and center hole e in Fig. 4 are drilled or made with the same gage as for the holes in Fig. 5, except that the holes in Fig. 4 may be a trifle larger so that they will easily receive the dowel-pins that have been permanently connected into the part G as shown in Fig. 2 and Fig. 5. The said gage can be made in the form of a pattern, with the exact size and required number of holes drilled through a 15 suitable steel plate, and then tempered hard so that the drills can not wear the holes any larger. Such a pattern can be made to fit against one end of the joint A, while drilling into one of the parts, and then the 20 other side of the pattern to fit the same against the other part, while drilling the opposite holes in the last part. Any one versed in this art will know how to make such a pattern for this purpose.

25 30 This my invention of the improvements can be made in any ordinary square that is all ready made; by cutting it off square in one of the inch-marks with a saw; or, a die can be made to cut both the joint A and the perforation B at the same time, and then finished up according to my drawing and specification.

It will be noted, that the nearer the corner of the square, any loose joint be placed, the more uncertain it is about its squareness; 40 when the joint is made at the middle of one of the blades, then it can easily be seen if the edges of that blade are straight, if not straight when the joint is drawn up tight with the screw-shell C then it can 45 easily be adjusted by cleaning off something that may have lodged in the joint, as rust, dirt, etc., otherwise it can not with ordinary use become off its alinement.

Having thus fully described my invention what I claim as new and desire to secure by Letters Patent of the United States is:

50 In a device of the class described, a main section provided with a plurality of holes, a separable section provided with a plurality of dowel pins to register with said holes in the main section, one of said dowel pins provided with screw threads, the main section provided with a perforation into which the extremity of the threaded dowel 55 pin extends, a threaded retaining pin on the main section located in the perforation of the main section into which the threaded dowel pin extends and in axial alinement 60 with the threaded dowel on the separable section and a screw shell or nut arranged to be screwed from one to the other of the two alined threaded pins.

CHARLES A. BENSON.
